UNITED STATES PATENT OFFICE.

JOHN WELLS KING, OF JAMESTOWN, NEW YORK.

DESIGN FOR A SPOON OR SIMILAR ARTICLE.

SPECIFICATION forming part of Design No. 20,909, dated July 7, 1891.

Application filed May 5, 1891. Serial No. 391,692. Term of patent 7 years.

To all whom it may concern:

Be it known that I, JOHN WELLS KING, a citizen of the United States, residing at Jamestown, in the county of Chautauqua and State 5 of New York, have invented and produced a new and original Design for the Handles of Spoons and like Table-Ware, of which the following is a specification.

Reference is to be had to the accompanying 10 drawings, forming a part of this specification, in which similar letters of reference indicate corresponding parts in both the figures.

Figure 1 is a face view of a spoon embodying my design in the handle thereof, and Fig. 15 2 a back view thereof.

The object of my invention is to produce a souvenir design for spoons and the like embodying symbols remindful of Chautauqua, and to this end have utilized the portrait of 20 the founder of the Chautauqua Literary and Scientific Circle, and in connection therewith I employ a representation of the Chautauqua landing and a steamboat.

The letter A indicates the portrait, which 25 is shown set in a border a, made of scroll-work, the said portrait being on the face of the han-

dle at the outer end. Inward from the portrait the handle is beaded, as at a' a', the beads terminating at the ends in scrolls. On the reverse side of the handle appears the 30 representation of the landing, showing the building thereat, (indicated by the letter B,) in connection with which appears the representation of a steamboat, (indicated by the letter C.) The reverse side of the handle is 35 beaded, as at b, said beads being curved outwardly at the outer end, as at b', and the opposite curves join a curve b² of small radius at the extreme end of the handle.

I claim—

1. In a design for the handle of spoons or other table-ware, the front or obverse, as herein shown and described.
2. In the design for the handles of spoons and other table-ware, the back or reverse, as 45 herein shown and described.
3. The design for the handles of spoons and like table-ware, as shown and described.

JOHN WELLS KING.
